UNITED STATES PATENT OFFICE.

GEORGE EVANS, OF NEW YORK, N. Y.

DENTAL TOOL.

SPECIFICATION forming part of Letters Patent No. 390,576, dated October 2, 1888.

Application filed January 10, 1888. Serial No. 260,356. (No model.)

To all whom it may concern:

Be it known that I, GEORGE EVANS, a citizen of the United States, residing at the city, county, and State of New York, have invented 5 certain new and useful Improvements in Thermal Instruments for Dentistry, of which the following is a specification.

The invention relates to instruments for conveying heat to narrow channels or interstices 10 of the teeth—as the nerve-canals in the roots—for the purposes of drying the same preparatory to filling, or destroying live nerves by heat. Such instruments are commonly made of a bulb or mass of metal adapted as a reservoir 15 to store heat derived from a flame or other source, and to subsequently dispense the heat through a wire or probe extending from the bulb, whereby the application is made at points difficult of access.

20 The object of the present invention is to employ materials in the construction of this class of instruments such as will best and most effectually carry out their functions; and it consists in combining with the bulb or reservoir 25 part, consisting of any suitable heat-retaining metal—such as copper—a probe or point composed of silver, which, possessing greater thermal conductivity than other metals, I find in practice to materially increase 30 the efficiency of the instrument.

Referring to the drawings accompanying this specification, Figure 1 is a perspective view of the instrument inserted to the nerve-canal of a tooth; and Fig. 2, an enlarged side view of the instrument, showing the bulb in 35 section.

The bulb A, preferably of copper, is removably secured, as by a screw-threaded stud, a, to the separate holder B, preferably of a material which will not conduct heat to the hand 40 of the operator. The lower end of the bulb A is provided with a screw-thread to receive the threaded shank of the silver probe C, which is readily removable thereby, and may be easily substituted for different ones, or in event of 45 injury. The silver, being ductile, admits, furthermore, of repeated bending to accommodate the position of the cavity to be reached.

I claim—

A dental heat-applying instrument composed of a bulb-reservoir (as of copper) adapted for receiving and storing heat, and a probe of silver attached to and extending from said bulb, adapted to conduct the stored heat to a point of application. 50

GEORGE EVANS.
